UNITED STATES PATENT OFFICE.

OTTO C. LUTHER, OF ANAMOOSE, NORTH DAKOTA, ASSIGNOR, BY DIRECT AND MESNE ASSIGNMENTS, OF ONE-SEVENTH TO MARTIN HUBLOU, ONE-SEVENTH TO DANIEL J. MURPHY, ONE-SEVENTH TO WILLIAM H. CHAPEK, ONE-SEVENTH TO MATTHEW R. FRITZ, ONE-SEVENTH TO PAUL F. BIBOW, AND ONE-SEVENTH TO CONRAD MARTIN AND ONE-SEVENTH TO F. J. FUNKE, BOTH OF ANAMOOSE, NORTH DAKOTA.

ROAD-DRAG.

1,116,305.

Specification of Letters Patent.

Patented Nov. 3, 1914.

Application filed May 29, 1913. Serial No. 770,594.

To all whom it may concern:

Be it known that I, Otto C. Luther, a citizen of the United States, residing at Anamoose, in the county of McHenry and 5 State of North Dakota, have invented new and useful Improvements in Road-Drags, of which the following is a specification.

This invention relates to road drags, and has for its object to provide improved construction in the frame work of such devices, 10 and in the adjusting means for regulating the function thereof, and to enable improved results therewith in various ways, as will subsequently appear.

15 While it is generally agreed that roads should possess a certain slope toward the sides, this slope varies in different roads, and even on the same road, in different sections, or in the same section at different times. It 20 is not absolutely essential that the slope of roads be exact to a given degree, and it might be in some cases that the wear of the road would be such as would make it desirable to have the slope differ at one time 25 from another, in order to conserve the material or labor.

It is therefore an important object of this invention to enable my device to accommodate itself to the requirements of the road 30 with respect to the various inclinations which may be encountered.

It is also an important object to enable 35 the operation of the device to move the material engaged by the drag either toward the center of the road for its conservation, or toward the side, to facilitate its removal.

Under certain conditions it is found desirable in repairing or treating a road surface to chisel up a portion in order to enable 40 its ready distribution, while at others it is more desirable to simply drag the surface, or both functions may be required at one time.

It is therefore a further important object 45 to enable my device to meet these requirements without complication of construction, and by the use of simple adjustment of the machine which will be operable at will.

A further object is to provide improved draft connections with such devices. 50

An additional object is to provide means for connecting the units of the device so that it may be used for treatment of the entire width of a single track road in one operation, or may be arranged to operate on one 55 side of a wide thoroughfare, as found desirable.

Additional objects and advantages will appear, some of which will be apparent from the following description and from the 60 drawings in which,

Figure 1, is a top view of the invention, Fig. 2 is a top view showing the modified connection of the units. Fig. 3, is a rear view, Fig. 4 is a sectional view showing adjustment of the plates.

There is illustrated a drag comprising two similar unit sections 10, each comprising scraper plates 11, connected pivotally at their inner sides to the frame work 12 and 70 arranged in parallel and diagonally with respect to the axis of the shaft, as will be understood. The plates 11 may be formed in any suitable manner, and preferably have sharpened road engaging edges, adjacent 75 the front side of the plates. In practice I find it best to make these plates about five feet in length, although this proportion may be varied as required. The two sections or units are connected loosely to a central 80 heavy draw bar 14, suitably for vertical oscillation relatively, to such degree as necessary to allow the two units to conform to the slope of the road surfaces engaged respectively. At the outer sides of the units 85 there are located secondary draw bars 15.

The frame 12 comprises two angle pieces 16, each having a long arm 17, and a short arm 18, with central flat connecting portions 19, the connecting portions of the members 90 16 in each unit are parallel and have registered apertures therethrough receiving a suitable securing bolt 20. Held between the portions 19 on each unit there is the central supporting portion 21 of a double segment 95 element having oppositely extending fore and

aft apertured segments 21 concentric to a line to the adjacent forward or rear end of the arms of the frame 12 as the case may be. The extremities of the arms of the frame 12 are provided with horizontal eyes, 22, in which are engaged hooks 23 carried by brackets 24 secured to the inner sides of the plates 11. The brackets 24 comprise a body portion or web 25 suitably apertured for engagement 10 of bolts to hold the bracket to the plates 11, and provided with one arm 26 extending at right angles to the plate from its inner side, and a second arm 27 extending longitudinally from the plate at the same height as the arm 26. On this account, the brackets are interchangeable from one to another of the plates 11, without modifying their use. The hooks 23 are so formed that the eyes 22 of the frame 12, can not be easily dislodged therefrom, and the weight of the frame will tend to hold the parts in proper operative relation, as will be readily understood. The outer ends of the arms 27 are provided with horizontal eyes 28, those of 15 the inner end of the plate 11 being coengaged with vertical eye portions 29 carried on the central draw bar 14. This draw bar and those 15 have their extremities offset upwardly, to facilitate the connection of a 20 swingle tree or the like for ordinary draft connections. The bars 15 are longitudinally slotted to allow the eyes 28 to be projected therethrough, for free rotation of the round portions of the arms 27 in the slot, and the 25 engagement of the pin 30 through the eyes outwardly of the bar, this pin being secured in place by a cotter pin in the usual manner. This construction allows free rotation of the plates for adjustment as will be 30 subsequently described.

Secured centrally on the inner side of the plates there is an upwardly extending lever 32, having a pin 33 engaged therethrough for insertion in the apertures of the segments 21 thereadjacent, by means of which lever the respective plates are adjusted at the inclination desired, and held so by the segments 21. Each lever 32 has a suitable guide staple 31 thereon by which the respective segment 21 is held in proper position. As long as the lever is properly engaged with one of the segments in operation position, the hooks on the arms 26 can not come to such position as to become disengaged from the frame 12, but in the event that it is desired to detach the plate from the frame, it is only necessary to throw the lever to the inner limit of its movement, when the hooks can be readily disengaged 50 from the eyes 22. Thus in the event that it is necessary or desirable to arrange both units of the device with the plates in alinement, the plates of one frame are disengaged from the frame 12, and the frame itself inverted, so that the long arms will be con-

nected to those brackets before connected to the short arms. The revoluble mounting of the segments between the angle pieces of the frame permits the segments to be adjusted on the upper side of the frame when inverted. It will be seen that the forward plates may be set at such angle as to perform a chisel function upon the road surface, while those at the opposite end are set with a forward inclination from their engaging edges, so that loosened materials will be spread and forced downwardly instead of further loosened, or all of the devices may be set at a common angle to the horizontal, to perform like functions.

The device as shown in Fig. 1 is arranged for use upon a narrow road, and the draft connections are so made that loosened materials will be forced toward the center of the road. In the event that it should be desired, however, the draft connections may be made with the opposite ends of the bars 14 and 15, when it will be seen that the loosened material will be forced to the outer sides of the road. The draft connections comprise a center element 35, adapted for engagement of a swingle tree in any suitable way, from which extend the links 36 having at their outer ends the hooks 37 engaged in the respective eyes of the side bars 15. From the rear side of the member 35, there is extended a heavy helical spring 37', carrying a hook 38 engaged in the eye 39 at the forward side of the center bar 14. By this arrangement the draft strain is applied evenly throughout the width of the device, and undue strains on the connections obviated.

When the units are connected with their plates in alinement, as shown in Fig. 2, the outer bar 15 on the rearmost unit is reversed, so that the long end A is projected forwardly, while the short end B is located at the rear. In this way, no matter what the connections of the units the draft bars have their forward ends in alinement, so that no modifications of draft connections will be required.

What is claimed is:

1. In a drag of the class described, a unit comprising at least front and rear scraper plates, a frame composed of two angle pieces each having a long and a short arm connected detachably and pivotally to respective plates for inversion of the frame at times, a lever fixed on each plate, segments carried by the frame in close relation to the levers concentric with the pivots of the plates, and adjustable detachable connections between the levers and the segments.

2. A device of the class described comprising two units each comprising a front and rear drag plate, longitudinally spaced brackets secured on the inner sides of each plate adjacent each end, each bracket having a longitudinal and a lateral arm pro-

vided with horizontal eyes, a central draft bar having vertical hooks connected with the eyes thereadjacent, a frame having hooks engaged respectively with the eyes of the lateral arms to hold the plates in diagonal relation to the bar, draft bars pivotally connected with the longitudinal arms at the outer ends of the plates and draft connections with the bars.

In testimony whereof I have hereunto set 10 my hand in presence of two subscribing witnesses.

OTTO C. LUTHER.
